UNITED STATES PATENT OFFICE.

WALTER S. MAYER, OF PHILADELPHIA, PENNSYLVANIA, ASSIGNOR TO THE
MACHEN & MAYER ELECTRICAL MANUFACTURING COMPANY, OF PHILA-
DELPHIA, PENNSYLVANIA, A CORPORATION OF NEW JERSEY

ELECTRIC SNAP-SWITCH.

No. 857,087.

Specification of Letters Patent.

Patented June 18, 1907.

Application filed January 4, 1907. Serial No. 350,786.

To all whom it may concern:

Be it known that I, WALTER S. MAYER, a citizen of the United States, residing in the city and county of Philadelphia, State of Pennsylvania, have invented certain new and useful Improvements in Electric Snap-Switches, of which the following is a specification.

My invention relates to an improvement in electric snap switches, and it has for its object to provide a switch, the mechanism of which is simple and efficient in operation.

My invention resides in the combination and arrangement of parts as hereinafter described in detail in the specification, set forth specifically in the claims, and as illustrated in the accompanying drawings, to which reference is to be had for a clearer understanding of my invention, and in which

Figure 1 is a view showing the receptacle or casing in section and the operative parts in side elevation; Fig. 2 is a side elevation of the operative parts, portions of certain of the parts being broken away; Fig. 3 is a view looking to the left in Fig. 1; Fig. 4 is a side elevation of a controlling or operating lever; Fig. 5 is a view looking to the left in Fig. 4; Fig. 6 is a view, showing portions of supporting lugs; Fig. 7 is a side elevation of a pivoted lever, to which the push buttons are connected; Fig. 8 is a bottom edge view of the lever shown in Fig. 7; Fig. 9 is a side elevation of a portion of the lever shown in Fig. 7 with a pivoted link connected thereto; Fig. 10 is a view looking to the left in Fig. 9; Fig. 11 is a side elevation of a lever which is associated with the lever shown in Fig. 7; and Fig. 12 is a view looking to the left in Fig. 11.

In the drawings, —1 designates a receptacle or casing of suitable insulating material, as, for instance, porcelain, in which the operating parts of my device are located.

2 designates a cover plate extending over the said receptacle, and 3 designates the outside cover plate to which the cover plate 2 is secured.

5 and 6 designate lugs depending from the plate 2. 7 designates a shaft mounted in the lower end portions of the lugs 5 and 6. 10 50 designates an energizing member consisting of a coiled wire spring, the opposite ends of which are crossed, and extend upon the opposite sides of a portion 11 of the lever 12,

which is provided with or connected to a sleeve 13 which is supported upon the shaft. 55 The spring 10 is coiled around the sleeve 13. The portion 11 of the lever 12 is arranged in substantially parallel relation to the shaft 7. The end of the lever 12 upon the opposite side of the shaft 7 from the portion 11 is provided with teeth 15, which are adapted to be engaged by teeth upon the projection 16 from the central portion of the controlling lever 18, which lever or controller is pivotally connected at 20 to the lower end portion of the 60 downwardly extending lug 5. The toothed projection may be termed a gear segment. The opposite ends of the lever 18 are connected to the lever's ends of the push buttons 21. 65

The lever 18 is shaped, as indicated most clearly in Figs. 7 and 8, so that the central portion thereof, including the segmental toothed portion 16, may be located adjacent to or in contact with one of the downwardly 70 extending projections, as for instance 5, while the end portions of the said lever 18 are located toward the middle portion of the space between the lugs 5 and 6. The push buttons 21 extend through perforations in 75 the plates 2 and 3 and are respectively pivotally connected to the opposite ends of the lever 18.

22 designates a link which is pivotally connected to the middle portion of the lever 18 80 at a point 23 above the pivotal point of connection between the said lever 18 and the lug 5. The pivot connecting the link 22 and the lever 18 passes through a curved slot 24 in the lug 5. 85

By reason of the relationship between the point of connection 23 between the lever 18 and the link 22 and the point of pivotal connection between the lever 18 and the lug 5, it will be observed that a bell crank lever 90 effect is produced.

The outer, or, in the construction as illustrated in the drawings, the upper end of the link 22 is provided with a bearing lug 25, provided with a friction sleeve 26, which is 100 adapted to project into a slot 27 in the outer end of a lever or shifter 28, which is pivotally connected to the shaft 7. Opposite the bearing lug 25 the link 22 is provided with a projecting lug 29 which is adapted to engage 105 the outer sides of guide stops 30 secured upon

the lug 5. The lower end of the said lever is provided with a lateral extension 31. The end of the extension 31 is provided with an upwardly-extending portion 32, which is also 5 pivotally connected to the shaft 7.

It will be noted that the parts 28, 31 and 32, taken together, constitute a substantially U-shaped device, the opposite legs of which are pivotally connected to the shaft 7. The portion 31 is located between the opposite ends of the coiled spring 10.

The lower end of the depending lug 6 is provided with projections 35 at its opposite corners, which act as stops to engage the parts 11 and 31 to limit the movements of the levers 12 and 28.

40 designates binding posts which are secured to the casing 1 by means of screws 41. 42 designates contact brushes secured to the binding posts and 45 designates binding screws by means of which the line wires or cords are connected to the binding posts and placed in electrical connection with the contact brushes 42.

25 In the operation of my device, one of the buttons 20 is pushed inwardly, as indicated in Fig. 2 of the drawings, so that one end of the lever 18 is moved to a position lower than that of the other end. When this occurs, 30 the projection or gear segment 16 is moved through an arc of a circle and being in engagement with the teeth 15 upon the upper end of the lever 12 occasions movement of the lower end of the latter in a direction opposite to that of the movement of the projection or gear segment 16.

In view of the fact that the portion 11 of the lever 12 is located between the ends of the springs 10, its movement against one of the said ends occasions a tensioning of the said spring, as the other end thereof, which is located upon the opposite side of the portion 11 of the lever 12 and the portion 31 of the lever 28 is held against movement, by 45 reason of its contact with the said portion 31 of the lever 28.

Upon the initial inward or downward movement of a push button 21 (the inner or lower end of which is connected to one end of 50 the controlling lever 18), the upper end of the link 22 is moved upwardly or outwardly in the slot 27 of the shifter or lever 28 so as to carry the lug 29 into a position outside of or behind the stop 30. The lower end of the 55 said button being connected to the controlling lever 18 occasions movement of the same about its pivot and by reason of the connection between the said controlling lever and the tensioning lever 12, the coiled spring 10 is placed under tension or is energized. One 60 end of the said spring being in engagement with the part 31 connected to the shifter or lever 28 tends to occasion pivotal movement of the latter, but such pivotal movement is 65 prevented by reason of the fact that the lug

29 upon the upper end of the link 22 has passed to the outside of or behind one of the stops 30. However, as soon as the upper end of the link has moved upwardly a sufficient distance, such movement being occasioned by the lateral movement of the lower end of the link 22 which is pivotally connected to the controlling lever 18, the lug 29 passes above the stop 30, the upper ends of the lever or shifter 28 and of the link 22 are moved quickly about their pivots to the opposite side of the device under the influence of the energizing spring 10. Movement of the lever or shifter 28 occasions movement of the contact arms or poles 50 which are operatively connected to the said lever or shifter.

In the position indicated in Fig. 1 of the drawings, these contact arms or poles are in engagement with the contact brushes. Upon depression, however, of the key 20 upon the left hand side of the device, the spring 10 would be placed under tension, one end bearing upon the portion 31 connected to the lever 28, the end of the link 22 connected to the said lever 28 would slide upwardly in the slot 27, and when the point of connection between the said link and the lever had reached a position at the outer end of the said slot, the tension of the spring would be permitted to throw the lever 28 quickly to the opposite side of the device, carrying said contact arms or poles 50 out of engagement with the contact brushes 42.

Having thus described my invention, I claim:

1. In a device of the character described, the combination of a pivoted lever, the said lever being provided with a gear segment, means for occasioning movement of the said lever, a pivoted spring tensioning lever, one end of which is provided with teeth which are adapted to engage the teeth of the gear segment, a spring, the ends of which are located upon the opposite sides of a portion of the said spring tensioning lever, a pivoted snap lever, a portion of which upon one side of its pivotal point is located between the ends of the said spring, a link connected at one end to the first-named lever and having its other end movably connected to the snap lever, and a contact member operatively connected to the said snap lever.

2. In a device of the character described, the combination of a pivoted lever, the said lever being provided with a gear segment, means for occasioning movement of the said lever, a pivoted spring tensioning lever, one end of which is provided with teeth which are adapted to engage the teeth of the gear segment, a coiled wire spring, the ends of which are located upon the opposite sides of a portion of the said spring tensioning lever, a pivoted snap lever, a portion of which upon one side of its pivotal point is located between the ends of the said spring, a link con-

ected at one end to the first-named lever at a point to one side and above the pivotal point of said lever, the other end of the said link being pivotally and slidably connected to an end portion of the said snap lever, and means to prevent pivotal movement of the said snap lever during the movement of the said first-named lever to place the said spring under tension, and a contact member

10 operatively connected to the said snap lever.

3. In a device of the character described, the combination of a contact member, means for supporting the same including a shifter, means for energizing said shifter, a controller for imparting energy to the said energizing means, means interposed between the said controller and the said shifter for controlling the movement of the latter, the said interposed means being pivotally connected to the controller and slidably connected to the shifter.

4. In a device of the character described, the combination of a contact member, means for supporting the same including a shifter,

means for energizing said shifter, a controller for imparting energy to the said energizing means, a link interposed between the said controller and the said shifter and operatively connected to each of them, and means co-operating with the said link to hold and release the shifter.

5. In a device of the character described; the combination of a contact member, means for supporting the same including a shifter, means for energizing said shifter, a controller for imparting energy to the said energizing means, a link pivotally connected at one end to the said controller, and slidably connected at its other end to the said shifter, a stop adapted to contact with the said link for the purpose set forth.

In testimony that I claim the foregoing as my invention, I have hereunto signed my name this 31st day of Dec. A. D. 1906.

WALTER S. MAYER.
